UNITED STATES PATENT OFFICE.

JOHN R. MEDLEY, OF ATLANTA, GEORGIA, ASSIGNOR TO ATLANTA PAPER COMPANY, OF ATLANTA, GEORGIA, A CORPORATION OF GEORGIA.

FOLDING BOX.

No. 797,446.

Specification of Letters Patent.

Patented Aug. 15, 1905.

Application filed February 10, 1905. Serial No. 245,132.

To all whom it may concern:

Be it known that I, JOHN R. MEDLEY, a citizen of the United States, residing at Atlanta, in the county of Fulton and State of Georgia, have invented certain new and useful Improvements in Folding Boxes; and I do hereby declare the following to be a full, clear, and exact description of the invention, such as will enable others skilled in the art to which it appertains to make and use the same.

My invention relates to an improvement in folding boxes; and the object of my invention is to produce a neat and cheap folding box and one which when unfolded for the purpose of holding articles will not have any creases in its sides and will be rigid and substantial.

My box is especially designed for collapsible boxes and is usually made of pasteboard; but obviously it is not confined to this use, and it may be made of any desired material.

With these objects in view my invention consists in the construction and combinations of parts, as hereinafter described and claimed.

In the accompanying drawings, Figure 1 is a perspective view of a box made in accordance with my invention when opened and ready for use. Fig. 2 is a view of the same when folded flat for shipment, and Fig. 3 is a plan view of the blank from which the complete box is made.

In Fig. 3, *a* represents the bottom of the box, provided with slits *b*, cut-away portions *c*, and flaps *d*, located on two sides thereof, said flaps being beveled off toward one end. The main portion of the blank is divided into a number of parts *e*, *f*, *g*, and *h*, preferably four, although any number may be used. The part *e* is provided with a flap *i*, located on its end. The part *f* is provided with a flap *j*, located on its side. The part *g* is provided with an extension *k* on its side, cut away, as shown at *l*, and beveled off, as shown at *m*, and the part *h* is provided with an extension *n* with its sides cut away, as shown at *o*. The dotted lines in Fig. 3 represent creases or scored marks.

As said before, the body portion of the box is usually made of a single blank. (Shown in Fig. 3). After the blank has been stamped out the four parts *e*, *f*, *g*, and *h* are bent around to form a rectangle, the flap *i* overlapping the end of the part *h* and being pasted or otherwise secured thereto. The extension *k*, to which it is secured, and the flap *j* are secured on top of one of the edges of the bottom *a*.

The box may then be folded into the position shown in Fig. 2. In case, however, extra large sizes of boxes are to be made the body portion can be stamped out of one or more blanks, which can then be attached together by gluing or in any other way, as desired. In all ordinary cases the body portion is made of a single blank.

It should be noted that the slits are inclined with relation to the crease *a* in the bottom of the box, these slits being arranged nearly, but not exactly, at right angles to said crease. The object is that when the box is folded up the projecting portions on the sides will exactly fit into and pass through the slots *b*, thus reinforcing the bottom of the box.

To unfold the box ready for use, it is simply necessary to open the box and push the bottom down, whereupon the corners *q* and *r* will pass through the slits *b* in the bottom of the box, firmly locking the same in position. Cut-away portions *c* are provided, so that if the box is opened quickly or carelessly the points *q* and *r* will enter the slits *b* readily. When the box is unfolded or set up for use, the flaps *d* are of course bent up parallel to the sides of the box and serve to strengthen it.

I preferably provide a stop *s*, Fig. 1, so that when the box has once been opened it will be locked in that position until it has been forcibly closed. This is not absolutely necessary, however, as the overlapping portions in the bottom of the box firmly hold it in position. Two of these stops may be provided, if desired, one over each of the flaps *d*.

Having thus described my invention, what I claim is—

1. A body-blank for a box having a creased bottom, made in one piece and provided with slits inclined with relation to the crease in said bottom, and parts arranged to fold up to form the sides of the box, two of said parts being provided with extensions adapted to readily engage the slits in the bottom of the box when the box is unfolded, said extensions acting as stiffeners or braces for the bottom of the box, substantially as described.

2. A body-blank for a box composed of a creased bottom made in one piece and provided with one or more flaps and also provided with slits arranged at an angle to the crease in said bottom, and four parts arranged to fold up to form the sides of the box, two of said parts being provided with flaps and the other two

of said parts being provided with extensions terminating in pointed portions adapted to readily engage the slits in the bottom of the box when the box is unfolded, said bottom and side parts being separated from each other by creases, and said extensions serving to strengthen the bottom of the box, substantially as described.

3. A box-body including four parts adapted to form the sides of the box, one of said parts being provided with a flap adapted to fold against another of said parts, a second one of said parts being provided with a flap adapted to engage the bottom of said box, a creased bottom made in one piece and provided with slits arranged at an angle to the crease in said bottom and provided with a plurality of flaps, and extensions carried by two of said side parts adapted to readily engage the slits in the bottom of the box when the latter is unfolded, substantially as described.

4. A box-body composed of four parts

adapted to fold up into a rectangle to form the sides of said box, one of said parts being provided with a flap adapted to engage another of said parts when the box is made up, a second one of said parts being provided with a flap adapted to engage the bottom of said box when the box is made up, and the other two parts being provided with extensions terminating in sharp points, a bottom for said box provided with slits and cut-away portions and having flaps on one or more of its sides, and a stop secured to one of said sides and adapted to engage one of said flaps when the box is opened to secure the same in its opened position, substantially as described.

In testimony whereof I affix my signature in presence of two witnesses.

JOHN R. MEDLEY.
